UNITED STATES PATENT OFFICE.

BAXTER P. HAMILTON, OF RIVER EDGE, NEW JERSEY, ASSIGNOR TO AMERICAN TELEPHONE AND TELEGRAPH COMPANY, A CORPORATION OF NEW YORK. *

TELEGRAPH REPEATER.

Application filed May 7, 1924. Serial No. 711,684.

To all whom it may concern:

Be it known that I, BAXTER P. HAMILTON, residing at River Edge, in the county of Bergen and State of New Jersey, have invented certain Improvements in Telegraph Repeaters, of which the following is a specification.

This invention relates to telegraph repeater sets and more particularly to a "universal" type of telegraph set over the local circuits of which repeating may take place from a plurality of different types of telegraph channels terminating at a station.

Among the different types of telegraph channels terminating at a station may be found open wire bridge polar duplex channels, differential polar duplex metallic channels operating over cables, open wire carrier telegraph channels, voice frequency telegraph channels and other types of telegraph channels. These various telegraph systems differ from each other in many respects due to the fact that they were developed at different times and also because different electrical conditions had to be met in each instance, and hence it has been the practice to provide at the station at which the lines of these systems terminate different types of repeater sets or local circuits for each type of channel or system. The apparatus required and the mechanical arrangement of the repeater sets required for the different channels has differed radically in each instance. Obviously a station at which only one type of telegraph set was utilized would present great advantages from the standpoint of flexibility, maintenance, and operation over a station employing a number of different types of sets. Accordingly it is the main purpose of this invention to provide a "universal" type of repeater set, or one suitable for use with a plurality of different channels and over the local circuits of which repeating may take place from a plurality of the different types of telegraph channels at the station. Other features and objects of the invention will appear more fully from the detailed description herein-after given.

The invention may be more fully understood from the following description together with the accompanying drawing in the Figures 1, 2, 3, and 4 of which the invention is illustrated. Figs. 1 and 2 when taken

together illustrate a circuit diagram of the repeater set, while Figs. 3 and 4 show the switching arrangements for connecting the relays in different positions in the local circuit.

In the circuit diagram of Figs. 1 and 2 are shown several different types of telegraph circuits terminating at a station. An open wire channel and standard composite set is shown terminating in jack J_1 . A metallic channel together with a metallic composite set and an artificial cable is shown terminating in the jacks J_2 and J_3 . A carrier channel with a schematic showing of detector and oscillator is shown terminating in jacks J_4 and J_5 . Other different types of channels might also be shown but the above types are sufficient for purposes of illustrating the invention. The universal repeater set is shown terminating in the plugs P_1 and P_2 adapted to be connected with the jacks above mentioned. The repeater set includes switching arrangements whereby the relays may be connected in the circuit in different positions. A receiving relay 1 may be connected in the circuit as shown when a connection is established with an open wire channel. The same receiving relay 2 may be connected in the circuit in the manner shown when a connection is established with a metallic channel and the same type of receiving relay 3 may be inserted in the switching arrangements and connected in the circuit in the manner shown when a connection is established with a carrier channel. The contacts of the relays 1, 2 and 3, respectively, are termed the pole changers 4, 5, and 6. A conductor 24 is shown connected to these pole changers and also connected with conductor 30 terminating in jack J_6 of the receiving leg. The pole changers will establish connections between conductor 24 and the oppositely poled receiving leg batteries associated with jacks J_6 and J_7 . By this arrangement impulses of opposite polarity may be transmitted out over the receiving leg under control of the relays 1, 2 or 3.

The sending arrangements of the repeater set comprise switching arrangements whereby the sending relays may be connected with the sending leg in different ways depending upon the type of line or channel with which a connection is established. For example, the sending relay 13 might be connected

with the sending leg in the manner shown when a connection was established with an open wire line. The same sending relay 12 might be connected in the circuit as shown when a connection was established with a metallic line and the same type of sending relay 11 might be connected in the circuit as shown when a connection was established with a carrier line. A break relay 10 and a meter 9 are also provided. The armatures 15, 16, 17 and 18 of the sending relays 11, 12, and 13 control the application of current impulses over circuits of the repeater set to the plugs P_1 and P_2 and thence to the connected line. In the cases of a connection with a metallic or open wire channel this current is supplied from the line batteries connected to the contacts of key K_3 . Other details of the circuit arrangements of the repeater set will appear more fully from the following description of its operation.

In Figs. 3 and 4 are shown types of switching arrangements suitable for connecting the relays in the circuits of the repeater set. In Fig. 3 is shown a relay 30 mounted on a base 30'. Affixed to the base are the holding plugs 51, 52, 53, and 54. Projecting through the base are the contact plugs of the relay 31 to 42 inclusive. In Fig. 4 is shown a jack panel 55 having jacks numbered with the added designation prime to fit the correspondingly numbered plugs of the relay. The plugs of the relay are simply inserted into the jacks of the panel to connect the relay in the circuit in the manner illustrated in the circuit diagram. Other suitable switching arrangements might be employed however, if desired.

The operation of the arrangements of the invention is as follows: For operation with an open wire channel a receiving relay 1 is connected in the circuit as shown by being plugged into the proper jack and the plug P_1 is inserted in the jack J_1 . The key K_1 will also be thrown to the right. The above operations will allow a circuit to be completed from the open wire channel through the tip contacts of jack J_1 and plug P_1 , over conductor 60, left-hand windings of relay 1, conductor 61, upper winding of meter 8, conductors 62 and 63, right-hand windings of relay 1, to the artificial line 7 and ground. Accordingly, the relay 1 will be actuated by the current impulses coming in over the open wire channel. A parallel circuit with the above traced circuit will also be closed through the lower winding of meter 8 by the actuation of key K_1 as follows: from conductor 61, over conductor 64, contact of key K_1 , conductor 65, lower winding of meter 8, conductor 66, contact of key K_1 , to conductor 63 and thence as previously traced. Accordingly, the impulses coming in over the open wire chan-

nel will operate the relay 1 which in turn will actuate the pole changer 4. The pole changer 4 will connect positive or negative battery to conductor 24 in the following manner: With the battery reversing key K_2 thrown to the right and the duplex key K_5 thrown to the full position positive battery will be applied to the upper contact of pole changer 4 as follows: from positive battery connected to jack J_7 , conductor 67, conductor 68, lower right-hand contact of key K_2 , conductor 69, conductor 70, contacts of key K_5 , conductor 27, and over conductor 26 to the upper contact and armature of pole changer 4 from whence it may be applied to conductor 24. Negative battery may be applied to the lower contact of pole changer 4 as follows: from negative battery connected to jack J_6 , conductors 74 and 75, upper right-hand contact of key K_2 , conductor 76, conductor 28, conductor 25, to the lower contact and armature of pole changer 4, from whence it may be applied to conductor 24. From conductor 24 these impulses of different polarity may be applied to the receiving leg as follows: from conductor 24, conductor 29, contacts of key K_5 , conductor 71, contacts of key K_4 , conductor 72, left-hand contact and armature of relay 19, conductor 73, contacts of key K_4 , over conductor 30 to jack J_8 of the receiving leg and thence to a subscriber's set if desired. If a connection is established with a metallic channel the plugs P_1 and P_2 are plugged into the jacks J_2 and J_3 , respectively. Impulses from the metallic channel will then be transmitted through the metallic receiving relay 2, which will be connected in the circuit as shown, as follows: from the upper contacts of jack J_2 and plug P_1 , conductor 77, lower windings of relay 2 and meter 8, conductor 78, and upper contacts of plug P_2 and jack J_3 to the artificial line of the metallic channel; and also from the lower contacts of jack J_2 and plug P_1 , over conductor 79, upper windings of relay 2 and meter 8, conductor 80, lower contacts of plug P_2 and jack J_3 , to the artificial line. Accordingly the impulses from the metallic channel will operate the metallic receiving relay 2, which in turn will control the pole changer 5. In a similar manner as already pointed out with respect to the pole changer 4 potentials of opposite polarities will be applied to the contacts of pole changer 5, and thence to the conductor 24, and from thence to the receiving leg J_8 as heretofore pointed out. Accordingly the impulses from the metallic channel will be repeated by the relay 2 to the receiving leg and thence to the subscriber's set if desired. If a connection is established with a carrier channel the plugs P_1 and P_2 are inserted in the jacks J_4 and J_5 , respectively, and the carrier receiving

relay 3 is plugged into the circuit as shown and key K_1 is thrown to the left. The impulses from the detector will be transmitted to the relay 3 as follows: from the upper contacts of jack J_4 and plug P_1 , conductor 77, conductor 81, winding of relay 3, conductor 82, lower winding of meter 8, conductor 83, winding of relay 3, conductor 84, conductor 79, to the lower contacts of plug P_1 and jack J_4 . The impulses from the carrier channel thus transmitted through the relay 3 will cause the relay to operate to control the pole changer 6. The pole changer 6 is arranged in a manner similar to pole changers 5 and 4 heretofore described and serves to apply current impulses to the receiving leg as heretofore described.

The sending arrangements of the repeater set operate in the following manner: A subscriber's set may be connected with the sending leg 86 through the jack J_5 . If a connection is to be established with an open wire channel an open wire sending relay 13 will be plugged into the circuit in the manner shown. The key K_3 would be thrown to the right and the plug P_1 inserted in the jack J_1 and key K_5 would be thrown to the right. The impulses from the subscriber's set will then be transmitted over the following circuit: from the subscriber's set over conductor 86, contacts of key K_6 , conductor 87, right-hand armature and contact of relay 19, conductor 89, upper contacts of key K_5 , conductor 90, upper winding of the open wire sending relay 13, upper winding of break relay 10, meter 9, conductor 201, contacts of key K_5 , conductor 202, to the sending leg battery. Accordingly, these impulses will operate the open wire sending relay 13 which will in turn operate its armature 18, the contacts of which are connected to conductors 93 and 94. Batteries of opposite polarity are connected to conductors 93 and 94 over the contacts of key K_5 . Accordingly, potentials of opposite polarity will be applied to the armature 18 and from thence will be transmitted over the following circuit: from armature 18, conductor 95, conductor 96, conductor 97, meter 8, left-hand winding of relay 1, conductor 60, upper contacts of plug P_1 and jack J_1 to the open wire channel. It is pointed out that a balancing circuit is also provided for the lower windings of the sending relays as follows: from meter 9, lower winding of break relay 10, lower winding of open wire sending relay 13, conductor 91, lower contacts of key K_5 , conductor 92, through a balancing resistance to ground. If a connection is to be established with a metallic channel, a metallic sending relay 2 will be plugged into the circuit as shown, the plugs P_1 and P_2 will be inserted in jacks J_2 and J_5 , and the key

K_3 will be thrown to the left. The impulses transmitted to the sending leg from the subscriber's set will operate the metallic sending relay 12 over the same circuit as heretofore traced with respect to the open wire sending relay 13. The relay 12 will operate its armatures 16 and 17, the contacts of which are connected to conductors 98 and 99. Batteries of opposite polarities are connected to these conductors over the left-hand contacts of key K_2 . Accordingly, potentials of opposite polarities will be applied to armatures 16 and 17 and thence over the following circuit: from armatures 16 and 17, over conductors 96 and 100, through the noise killer device 22, over conductors 101 and 97, meter 8, left-hand windings of relay 2, conductors 77 and 99 to the contacts of plug P_1 and jack J_2 , and thence to the metallic channel. A balancing circuit is also provided through the right-hand winding of relay 2 to the artificial cable to prevent the relay from operating at this time. If a connection is established with a carrier channel the plug P_1 is connected to the jack J_4 and plug P_2 and connected to jack J_5 and a carrier sending relay 11 is plugged into the circuit as shown. The impulses transmitted to the sending leg 86 from the subscriber's set will operate the carrier sending relay 11 over the same circuit as heretofore traced with respect to the metallic and open wire sending relays 12 and 13. The relay 11 will operate its armature 15 to connect and disconnect battery 102 to conductor 103. These impulses from armature 15 will be transmitted over the following circuit: from armature 15, conductor 103, conductor 78, upper contacts of plug P_2 and jack J_4 to the oscillator to operate it to send impulses out over the carrier channel in a well known manner.

The repeater set may furthermore be provided with a key K_9 which will control the relay 19 whereby the repeater attendant may signal in both directions if desired. A reversing key K_7 is also provided to reverse the connections of the polar sounner 20 when the battery connection is reversed by the contacts of the break relay 10. The keys K_4 to K_6 are monitoring keys, which when thrown to the left, operate to cut off the receiving and sending legs and to connect them directly to the receiving leg batteries.

While only three different types of telegraph channels have been illustrated it is understood that other and additional types of channels might be used with the universal repeater set of the invention. Accordingly, while the invention has been illustrated in certain specific arrangements which are deemed desirable it is understood that it is capable of embodiment in many and other

widely varied forms without departing from the spirit of the invention as defined in the appended claims.

What is claimed is:

- 5 1. A telegraph station, a plurality of different types of telegraph channels terminating thereat, a telegraph repeater set adapted to be associated with said channels and comprising a plurality of switching arrangements, a plurality of receiving relays adapted to be connected in said repeater set by said switching arrangements, each of said relays being suitable for operation with and being operated by current impulses coming 10 in over different ones of said telegraph channels, pole changers controlled by said relays, and a receiving leg whereby a connection may be extended from said set, said receiving leg being associated with said pole 15 changers whereby impulses of different polarities may be applied to said receiving leg.

2. A telegraph station, a plurality of different types of telegraph lines terminating 25 thereat, a telegraph repeater set, connecting means for connecting said repeater set with any of said lines, said repeater set comprising a plurality of switching arrangements, a plurality of sending relays adapted to be 30 connected in said repeater set by said switching arrangements, said sending relays being suitable for operation when a connection is established with different ones of said telegraph lines, a sending leg circuit to which 35 may be applied current impulses, said sending leg circuit being associated with said sending relays, pole changers controlled by said relays, and circuit arrangements where-

by current impulses may be transmitted from said pole changers to said connecting means. 40

3. A telegraph station, a plurality of different types of telegraph lines terminating thereat, a telegraph repeater set, connecting means for connecting said repeater set with any of said lines, said repeater set comprising a set of switching arrangements, a plurality of receiving relays adapted to be connected in said repeater set by said switching arrangements, said receiving relays being suitable for operation with and being operated by current impulses coming in over different ones of said telegraph lines, pole changers controlled by said receiving relays, a receiving leg whereby a connection may be extended from said set, said receiving leg being associated with said pole changers whereby impulses of different polarities may be applied to said receiving leg, a second set of switching arrangements, a plurality of sending relays adapted to be connected 50 in said repeater set by said switching arrangements, said sending relays being suitable for operation when a connection is established with different ones of said telegraph lines, a sending leg circuit to which 55 may be applied current impulses, said sending leg circuit being associated with said sending relays, pole changers controlled by said sending relays, and circuit arrangements whereby current impulses may be transmitted from said last mentioned pole 60 changers to said connecting means. 65

In testimony whereof, I have signed my name to this specification this 6th day of May 1924.

BAXTER P. HAMILTON.
